CLAIM

The ornamental design for a vibration sensor mount, as shown and described.

DESCRIPTION

FIG. 1 is a perspective view of a vibration sensor mount in accordance with the present invention;

FIG. 2 is a first end view of the vibration sensor mount of FIG. 1;

FIG. 3 is a first side view of the vibration sensor mount of FIGS. 1 and 2;

FIG. 4 is a second side view of the vibration sensor mount of FIGS. 1-3;

FIG. 5 is a second end view of the vibration sensor mount of FIGS. 1-4;

FIG. 6 is top view of the vibration sensor mount of FIGS. 1-5;

FIG. 7 is bottom view of the vibration sensor mount of FIGS. 1-6; and,

FIG. 8 is a cross-sectional view of the vibration sensor mount taken along lines 8-8 of FIG. 4.
